UNITED STATES PATENT OFFICE.

FRANKLIN R. WHITE, OF WATERBURY, CONNECTICUT, ASSIGNOR TO THE PATENT BUT-
TON COMPANY, OF WATERBURY, CONNECTICUT, A CORPORATION OF CONNECTICUT.

BUTTON.

Application filed July 30, 1924. Serial No. 729,014.

To all whom it may concern:

Be it known that I, FRANKLIN R. WHITE, a citizen of the United States, and a resident of Waterbury, in the county of 5 New Haven and State of Connecticut, have made and invented certain new and useful Improvements in Buttons, of which the following is a specification.

My invention relates to buttons, and more 10 particularly to that class thereof which are attached to the cloth or garment by means of a metal fastener.

The object of my invention is to provide 15 a button of the so-called "open top type", (that is, that type wherein the plunger of the attaching machine passes down through the open top of the button and heads or turns over the prongs of the fastener) which is made up of a back formed of sheet 20 metal and a front or top which has been stamped from a rod-like blank so as to possess any desired and ornamental configuration.

I have found that when the front or top 25 is made by the heading process it may partake of any desired configuration or it may have any desired ornamentation or inscription formed directly thereon. My novel button may therefore partake of the outline 30 of a four-leaf clover, a dog's head, or other fanciful shape or form, and being composed of some light metal such as aluminum will present a neat and pleasing appearance, will be light in weight, and the top being 35 of some thickness lends a substantial appearance to the button.

A further object is to accomplish the 40 aforementioned ends and at the same time provide a top or front with a centralized opening so as to admit the plunger of a button attaching machine to pass therein and properly head or rivet the prongs of a fastener to the button and without danger or likelihood of the top of the button being 45 distorted or marred.

A further object is to provide an improved securement or joint between the shell back of the button and the aluminum top, and with the foregoing and other objects 50 in view my invention resides in the novel button as illustrated in the accompanying drawing and hereinafter described and claimed, and in such variations and modifications thereof as will be obvious to those

skilled in the art to which my invention 55 relates, it being understood that changes may be made within the scope of what is claimed without departing from the spirit thereof.

The preferred embodiment of my invention 60 is disclosed in the accompanying drawing, wherein:

Figure 1 is a view in longitudinal section of my improved button secured to a 65 garment;

Figure 2 is a top plan view thereof;

Figure 3 is a bottom plan view of the button;

Figure 4 is view in section of the front 70 or top of the button prior to its secure-
ment to the back;

Figure 5 is a top plan view of the back of the button;

Figure 6 is a bottom plan view of the top 75 of the button; and

Figure 7 is a view similar to Figure 1 showing my improved button secured to a garment by a staple fastener.

Referring specifically to the several views, wherein similar reference numerals 80 designate corresponding parts throughout, my novel button is composed of a back B which is stamped from sheet metal so as to be relatively strong but light in weight.

The back B is of the usual construction 85 and includes the hollow hub 10, the imperforate base 11 and the outwardly projecting flange 12. Extending upwardly from the flange 12 is a peripheral rim 13.

The back as thus composed is of standard 90 form and to it I attach the soft metal front or top 14. The soft metal front is provided with the centralized opening 15 which lies directly above and is approxi- 95 mately equal in size to the internal diameter of the hub 10. The front or top 14 is preferably made by the heading process so as to be of any desired configuration or contain thereon any desired fanciful ornamentation and in addition is provided with 100 a smooth and rounded edge 16, downwardly from the under side of which projects the rim 17. The provision of the downwardly extending rim 17 forms an annular recess 18 which receives the peripheral rim 13 of the back therein. The two are then subjected to the action of 105 suitable swedging dies (not shown) where-

2
by the rim 17 is turned over upon the rim 13, the metal of the rim 17 being shaped so as to form a smooth continuation of the flange 12 of the back and thereby provide 5 a button of neat and pleasing appearance.

As illustrated in Figure 7, the back B' may be provided with an imperforate base which is adapted to be pierced by the 10 prongs 20 of a staple fastener, the ends of which prongs are then turned over by a plunger (not shown) which passes down through the opening 15' in the top of the button.

While I have spoken of the top as being 15 made of aluminum, it will be readily appreciated that it may be made of any soft metal, but preferably a non-ferrous metal or alloy, so as to readily assume any desired configuration or shape and partake 20 of a high and pleasing polish or may be lacquered if desired.

My improved button as thus formed is considerably more economical to construct 25 than a button formed entirely of one piece of metal and at the same time it possesses practically all of the advantages and desirable features of the same. The provision of the opening within the top of the button allows the button to be used in a button 30 attaching machine and insures that there will be no danger or likelihood of the top of the button becoming marred or distorted as it is fastened to the cloth or garment.

Having thus fully described and ex-

plained my invention, I claim and desire to 35 secure by Letters Patent:

1. A button comprising a back stamped from sheet metal and including a hub and an outwardly extending flange; a front member of comparatively soft metal headed 40 to the desired configuration and provided with a recess in the rear face thereof and a centralized opening extending therethrough for the reception of a plunger of a button-attaching machine, the flange of 45 the back extending into said recess and permanently anchored therein.

2. A button comprising a back including a hub, an outstanding flange, and an upwardly extending rim, a front member 50 having a centralized opening extending therethrough for the reception of a plunger of a button-attaching machine, said front member provided adjacent its edge with a downwardly extending rim defining a 55 recess therebetween, the rim of the back extending up within the said recess and the metal of the rim of the front member bent over upon the rim of the back and forming a smooth continuation of the flange 60 of the back.

Signed at Waterbury in the county of New Haven and State of Connecticut this 24th day of July A. D. 1924.

FRANKLIN R. WHITE.
